(57) **CLAIM**

The ornamental design for a surveillance camera, as shown and described.

DESCRIPTION

Figure 1.1 is a perspective view of the surveillance camera; Figure 1.2 is a back view of the surveillance camera; Figure 1.3 is a left side view of the surveillance camera; Figure 1.4 is a front view of the surveillance camera; Figure 1.5 is a top view of the surveillance camera; Figure 1.6 is a bottom of the surveillance camera; Figure 1.7 is a right side view of the surveillance camera; Figure 2.1 is a perspective view of the surveillance camera; Figure 2.2 is a back view of the surveillance camera; Figure 2.3 is a left side view of the surveillance camera; Figure 2.4 is a front view of the surveillance camera; Figure 2.5 is a top view of the surveillance camera; Figure 2.6 is a bottom of the surveillance camera; and Figure 2.7 is a right side view of the surveillance camera. All coloring [black, gray, and white] discussed in the reproductions forms part of the claimed design. The broken lines in the reproductions depict portions of the surveillance camera that form NO part of the claimed design.

1 Claim, 6 Drawing Sheets(56)
